His Attorney.

UNITED STATES PATENT OFFICE

2,561,859

METHOD OF SHAPING VITREOUS TUBES

Alfred Greiner, Cleveland Heights, Ohio, assignor
to General Electric Company, a corporation of
New York

Application November 3, 1949, Serial No. 125,315

6 Claims. (Cl. 49—92)

1

This invention relates to methods of making vitreous tubes having straight parallel portions and particularly to methods of making U-shaped glass tubes useful as envelopes for discharge devices, such as fluorescent and germicidal discharge lamps.

Glass tubes having a U-shape have heretofore been formed by bending a straight tube either by hand or mechanically. In order to get a satisfactory U-bend, so that the legs will be parallel and of the same length, the tube must be heated exactly in the middle and quickly bent to the desired shape. This inherently results in a thin wall on the outside of the bend. If a heavier-walled tubing is used in order to make a practical outer wall thickness at the bend, the inner wall tends to corrugate or buckle. This effect is particularly troublesome when a sharp bend is made, i. e., when very little spacing is desired between the legs of the finished tube. The bending operation also becomes much more difficult as the diameter of the tubing is increased to the size usual for fluorescent or germicidal lamp envelopes.

An object of my invention is to provide a method of making a vitreous tube having parallel, closely-spaced straight portions united by a curved portion and having a substantially uniform wall thickness throughout.

Another object is to provide a method of forming a U-shaped tube having closely spaced legs.

A further object of my invention is to provide a method whose effectiveness in forming U-shaped tubes is independent of the tube diameter and which is particularly useful in easily forming U-tubes of a large diameter.

A feature of my invention which attains the above objects and obviates the disadvantages of the prior art methods consists of forming a composite tube having closely spaced parallel straight portions from pieces of straight tubing by joining the pieces in the manner hereinafter described.

Additional features and objects of my invention will appear from the following description and from the accompanying drawing in which, Fig. 1 is a perspective view of two open ended glass tubes held in spaced parallel positions in a dual compression rubber chuck, the tubes are shown broken along their length to indicate that they are of greater length than shown in the drawing; Fig. 2 is a similar view of the lower end of the tubes showing a pair of gas burners for heating them and a glass working tool; Fig. 3 is a bottom plan view after the tubes shown in Fig. 2 have been joined by the tool; Fig. 4 is a

2

similar view of the joined tubes after continued heating of their juncture; Fig. 5 is a perspective view of the lower tube ends joined together and a pair of gas burners for heating the joined ends; Fig. 6 is a similar view of the tube ends closed and a fragmentary view of a glass working tool; and Fig. 7 is a front elevational view on a reduced scale of a U-shaped envelope made up of the two tubes, mounted in a mold and connected to a source of air under pressure.

Referring to Fig. 1 of the drawing, the method of making a U-shaped tube in accordance with my invention comprises the steps of gripping two glass tubes 1 and 2 adjacent one of their ends in a chuck having jaws 3 and 4 which holds the tubes 1 and 2 in closely spaced, side-by-side parallel positions with their lower ends terminating in the same plane. A pair of opposed gas ribbon burners 5 and 6 each having a series of aligned openings or jets are directed between the lower juxtaposed ends of the tubes 1 and 2 to heat their inside facing surfaces to the softening temperature of the glass. With the heated glass in a plastic condition, one blade of a pair of shears 7 is inserted in the lower end of each of the glass tubes 1 and 2, as shown in Fig. 2, and the softened wall portions of the tubes 1 and 2 are first pressed together and then cut by closing the blades of the shears 7. The walls of the lower open ends of the tubes 1 and 2 are thus united as shown at 8 in Fig. 3 into a composite wall common to both tubes 1 and 2. On continued heating by the burners 5 and 6, the composite wall approaches an oval shape in cross-section as shown in Fig. 4 and defines an outwardly opening cavity communicating with the bores of the tubes 1 and 2.

The outer opening of the cavity is then closed as shown in Figs. 5 and 6 by directing the opposed ribbon burners along the dotted line 9 transverse to the longitudinal axes of the tubes 1 and 2 to heat the glass in a narrow zone including line 9 to its softening temperature. The softened glass is then severed by the shears 7 along the dotted line 9 to close the opening as shown in Fig. 6. The cullet 10 drops off after severing. Obviously, the cullet 10 may be melted off by the burners in the usual manner and the use of the shears 7 eliminated. The melting off of the cullet 10 closes the opening as the cullet drops off pulling the softened glass walls together.

The preferred final step in making the U-shaped tube consists in shaping the bend by heating the glass which is to form the bend to its softening temperature by the usual gas flame used

in glass working, placing it in a suitably shaped split mold 11 (Fig. 7), with one open end closed by a stopper 12, and the other open end provided with a conduit 13 passing through a stopper 14 into the interior of the tube. The conduit 13 is connected to a source of air under pressure to blow the glass into the mold and shape the bend. After the bend has cooled and has been removed from the mold, the composite U-shaped tube may be made into a lamp by mounting electrodes in its ends, introducing an ionizable gas therein in the usual manner and sealing the tube.

The new method may be used successfully for making composite U-shaped tubes from two pieces of straight glass tubing of various diameters. For example, in making fluorescent discharge lamps and germicidal lamps, it is common to use a straight tube approximately 1½ inches in diameter as the lamp envelope. A U-shaped tube having this diameter and a separation of only approximately $\frac{1}{16}$ inch to $\frac{1}{4}$ inch between the legs is readily fabricated by the method described above without the disadvantages of variations in wall thickness or corrugated wall portions at the bend of the U-shaped tube characteristic of the prior attempts to bend a straight tube having a diameter of this order into a U-shape with a separation between the legs less than the diameter of the tube. When using 1½ inch diameter tubes to form a U-tube with a separation $\frac{1}{16}$ to $\frac{1}{4}$ inch between its legs, in accordance with the method of my invention, gas burners 3 inches long and $\frac{1}{8}$ inch wide are preferred in uniting the open ends of the tube as described in connection with Figs. 2 to 4. The tubes are cut longitudinally by the shears for a distance approximately 3 inches from their open ends. In the operation described in connection with Figs. 5 and 6 the tubes 1 and 2 are cut by the shears along the transverse line 9 approximately 1½ inches from their open ends to close the bottom of the composite tube. Of course, with tubes of other diameters, the above distance of the cuts may be suitably changed.

Obviously, the method described above may be used to make up a composite tube having any desired number of closely spaced parallel straight portions by joining the ends of the composite tube to the ends of pieces of straight tubing or to other similarly made composite tubes in the same manner that tubes 1 and 2 are joined together and the shape of mold 11 may be modified to shape the bends of such composite tube having a multiplicity of closely spaced parallel straight portions. Such tube is also useful as a discharge lamp envelope.

What I claim as new and desire to secure by Letters Patent of the United States is:

1. method of joining vitreous tubes to form a composite tube having closely spaced portions connected by a 180° curved portion which comprises mounting open end portions of a pair of vitreous tubes side-by-side and opening in the same direction, heating to a plastic condition and then pressing together and cutting through the facing wall portions of the tubes for a substantial distance inwardly from their open ends to form a composite wall common to and uniting said tubes, shaping the composite wall into an oval in cross section and to define an outwardly opening cavity communicating with the bores of the tubes and then closing the outer opening of the cavity.

2. The method of joining vitreous tubes to form a composite tube having closely spaced

portions connected by a 180° curved portion which comprises mounting open end portions of a pair of vitreous tubes side-by-side and opening in the same direction, heating to a plastic condition and then pressing together and cutting through the facing wall portions of the tubes for a substantial distance inwardly from their open ends to form a composite wall common to and uniting said tubes, shaping the composite wall into an oval in cross-section and to define an outwardly opening cavity communicating with the bores of the tubes, heating to a plastic condition the composite wall adjacent the outer opening of the cavity and pressing the plastic walls together to close the said opening.

3. The method of joining vitreous tubes to form a composite tube having closely spaced portions connected by a 180° curved portion which comprises mounting open end portions of a pair of vitreous tubes side-by-side and opening in the same direction, heating to a plastic condition the facing wall portions of the tubes for a substantial distance inwardly from the said open ends, progressively pinching together and immediately cutting through the plastic wall portions inwardly from the tube ends to unite the severed walls of the tubes into a composite wall common to both tubes, shaping the composite wall into an oval in cross-section and to define an outwardly opening cavity communicating with the bores of the tubes, and then closing the outer opening of the cavity.

4. The method of joining vitreous tubes to form a composite tube having closely spaced portions connected by a 180° curved portion which comprises mounting open end portions of a pair of vitreous tubes side-by-side and opening in the same direction, heating to a plastic condition the facing wall portions of the tubes for a substantial distance inwardly from the said open ends, progressively pinching together and immediately cutting through the plastic wall portions inwardly from the tube ends to unite the severed walls of the tubes into a composite wall common to both tubes, shaping the composite wall into an oval in cross-section and to define an outwardly opening cavity communicating with the bores of the tubes, heating to a plastic condition the composite wall adjacent the outer opening of the cavity, pressing the plastic sides of the oval-shaped wall together to close the outer opening and then molding the composite wall portion of the tube into a smooth rounded contour.

5. The method of forming a U-shaped vitreous tube having closely spaced legs which comprises vertically mounting two pieces of straight vitreous tubing in side-by-side parallel relation and spaced apart by the distance desired between the legs of the finished U-shaped tube, heating the inside facing surfaces of said tubes at the lower ends thereof to a plastic condition, pressing together and cutting through the said plastic inside facing surfaces at the equivalent of the point of tangency for a distance upward from the bottom of the tubes of approximately twice the tube diameter thereby uniting the walls of said tubes for said distance, further heating the composite wall so formed to increase the size of the transverse opening between said tubes defined by said wall, heating said wall to a plastic condition and pressing together and cutting through its plastic sides transversely to the axes of the united tubes and at the distance from 70 the bottom equal to a tube diameter to close the

bottom of the composite tube, and thereafter shaping the composite wall into a smooth rounded curve joining the legs of the U-shaped tube.

6. The method of forming a U-shaped vitreous tube having closely spaced legs which comprises vertically mounting two pieces of straight vitreous tubing in side-by-side parallel relation and spaced apart by the distance desired between the legs of the finished U-shaped tube, heating the inside facing surfaces of said tubes at the lower ends thereof to a plastic condition, pressing together and cutting through the said plastic inside facing surfaces at the equivalent of the point of tangency for a distance upward from the bottom of the tubes of approximately twice

the tube diameter thereby uniting the walls of said tubes for said distance, further heating the composite wall so formed to increase the size of the transverse opening between said tubes defined by said wall, heating said wall to a plastic condition in a narrow zone transverse to the axes of the united tube and at a distance from the bottom equal to a tube diameter or melt off the cullet and to close the bottom of the composite tube, and thereafter shaping the composite wall into a smooth rounded curve joining the legs of the U-shaped tube.

Certificate of Correction

July 24, 1951

ALFRED GREINER

It is hereby certified that error appears in the printed specification of the above numbered patent requiring correction as follows:

Column 6, line 8, for "or melt" read *to melt*;
and that the said Letters Patent should be read as corrected above, so that the same may conform to the record of the case in the Patent Office.
Signed and sealed this 15th day of January, A. D. 1952.
